[57] **CLAIM**

The ornamental design for a connecting coupling for joining structural members, as shown and described.

DESCRIPTION

FIG. 1 is an enlarged top perspective view of a connecting coupling for joining structural members showing my new design;

FIG. 2 is a front elevational view thereof;

FIG. 3 is a transverse sectional view taken towards the left of FIG. 2;

FIG. 4 is a side elevational view thereof taken from the left of FIG. 2;

FIG. 5 is a bottom plan view thereof; and

FIG. 6 is a top plan view thereof.
The rear of the coupling follows the configuration shown in FIGS. 3, 5 and 6.

FIG. 1

FIG. 5

FIG. 3

FIG. 4

FIG. 2

FIG. 6
